COLLAPSIBLE CARTON

Louis De Marco, Jr., Chicago, Ill., assignor to
 Superior Felt & Bedding Company, Chicago, Ill.,
 a corporation of Delaware

Application August 13, 1936, Serial No. 95,891

2 Claims. (Cl. 229—35)

This invention relates broadly to cartons, and more particularly to cartons of cardboard or light material which are collapsible.

An object of the present invention is to provide a carton that is especially adapted for use in shipping articles of furniture and more particularly to articles of furniture known in the trade as "studio couches".

A further object of the invention is to provide a collapsible carton wherein the same defines a pair of complementary telescoping sections, each of which is identically constructed; and wherein the structure of each is such as to provide reinforcements therefor at the places where the tying cord or the like will contact the carton structure as to cause wear thereon and the weakening thereof.

The invention, together with its objects and advantages will be thus understood from a study of the following description taken in connection with the accompanying drawings, wherein:

Figure 1 is a perspective view of a complete carton, embodying the features of the present invention.

Fig. 2 is a sectional view taken on the line 2—2 of Fig. 1.

Fig. 3 is a blank from which each section of the carton is formed.

Fig. 4 is an edge elevational view of the blank.

Fig. 5 is a perspective view of one of the sections of the carton in set-up position.

Referring to the drawings by reference numerals, it will be seen that the improved carton comprises a pair of complementary telescoping sections 5. Each of the sections 5 is formed from a single blank of cardboard or other suitable material which is preferably rectangular and is foldable on lines 6—6 to provide side walls 7 and bottom or central wall 8. It is also foldable on transverse lines 9—9 to provide end walls 10. It will be seen that the side walls and the end walls 10 are hingedly connected to the bottom 8.

Also the blank is slit on angular lines 11 to provide tongues or projections 12 for each of the wings or corner flaps 13 provided with the end walls 10. The wings 13 are formed by folding the blank on lines 14 constituting extensions of the fold lines 6.

Also the blank inwardly from the fold lines 9 and immediately adjacent the respective opposite end of the fold lines 6 is slotted as at 15 to receive the tongues 12 when the walls 7 and 10 are folded into right angular relationship to the bottom 8, as will be seen from a study of Fig. 5.

It will be seen that when the blank is folded to the position shown in Fig. 5, tongues 12 pass through the slots to the outer face of the bottom 8 and are then folded inwardly into overlapping engagement with the outer face of the bottom 8.

Thus the tongues 12 and slots 15 serve to hold the wings 13 of the ends 12 in right angular relationship to the ends 10, and to hold the ends 10 at right angles to the bottom 8.

When each of the sections 5 are set up as shown in Fig. 5, the carton is ready for use. The contents of the carton are placed in one of the sections 5 whereupon the other section 5 is telescoped onto the first mentioned section to provide a lid therefor as clearly suggested in Fig. 1.

When the sections are thus assembled in the telescoped relation, the tying cord 16 is then applied thereto and in this connection it will be seen that the portions of the cord are trained across the respective opposite ends of the carton, said parts of the cord are trained over the tabs 12 which latter then serve as a reinforcing means for the sections of the carton.

A carton embodying the features of the present invention will be found to have many features of advantage over the present type of cardboard cartons, which latter are generally provided with slots in the side walls thereof, while the wings of the said walls which fold into overlapping engagement with the respective opposite ends of the side walls are usually provided with tongues and engage the slots in the side walls, so that these tongues in no wise serve as a reinforcing means and wear surface for the carton as do the tongues 12 of the present invention.

It is thought that a clear understanding of the construction of a carton of this character will be had without a more detailed description.

Having thus described the invention what is claimed is:

1. A carton formed from a blank of flexible material cut and scored to provide a bottom and four side walls hingedly connected to the bottom, one pair of opposite side walls having integral corner flaps at opposite ends thereof lying against the inner surfaces of the other side walls, said corner flaps having downwardly extending projections inserted through slots provided at the juncture of the second named side walls and the bottom.

2. A carton formed from a blank of flexible material cut and scored to provide a bottom and four side walls hingedly connected to the bottom, one pair of opposite side walls having integral corner flaps at opposite ends thereof lying against the inner surfaces of the other side walls, said corner flaps having downwardly extending projections inserted through slots provided at the juncture of the second named side walls and the bottom, said projections being of such length

that they extend beyond said slots and have their outer end portions folded to overlie the outer face of said bottom.
